D. PARKS

MEANS FOR AND METHOD OF ASSEMBLING COMPOSITE HEEL BLANKS

Filed Jan. 31, 1924

UNITED STATES PATENT OFFICE.

DENNIS PARKS, OF ST. LOUIS, MISSOURI.

MEANS FOR AND METHOD OF ASSEMBLING COMPOSITE HEEL BLANKS.

Application filed January 31, 1924. Serial No. 689,790.

To all whom it may concern:

Be it known that I, DENNIS PARKS, a citizen of the United States, residing in the city of St. Louis and State of Missouri, have invented new and useful Improvements in Means for and Methods of Assembling Composite Heel Blanks, of which the following is a specification.

This invention relates to the art of making composite heels, comprising a leather base and a rubber tread or heel, and has special reference to improved means for centering the rubber heel on the leather base in assembling, and to a novel method of procedure by which the rubber heel is maintained in its position on the leather base in the movement of the heel blank through the container in which the parts are assembled.

In proceeding according to my invention, a container, such as is used in the well-known operation of log building, and of any desired length, is employed, such container having the general outline of a heel-blank. The rubber heel is first inserted in the container and then a leather lift or base, having paste applied to its flat side, is positioned on top of the rubber heel with the randed side of the base or lift uppermost, and then a plunger is operated to force the composite heel downward a given distance in the container.

In practicing this process, due to the fact that, after the heel-blank is made it must be trimmed and shaped as to its leather portion, the leather base or lift is larger than the rubber heel, and, therefore, projects beyond the same. It was soon found, in practice, that considerable care had to be exercised to properly position the leather base on the rubber heel, so that the two members would be centered with reference to each other. It was also found that as the heel-blank, composed of the leather base and rubber heel, was forced downward in the container, relative movement between the two parts would occur, so that when the heel-blank emerged from the bottom of the container, the leather base would not project uniformly from the sides of the rubber heel. In other words, the leather base would project farther from the edge of the rubber heel at one side than at the other, with the result that when the heel was trimmed, more of the rand would be cut off on one

side than on the other, so that the randed 55 surface would be higher at one side of the heel than at the other.

To overcome this objection, I have devised the means and method of procedure herein-after described, whereby the leather base 60 will be initially positioned correctly on the rubber heel, and the two parts will be maintained in this position during the passage of the column of heel blanks through the container.

The invention, as to its mechanical feature, consists, essentially, in the provision of yieldable guide members projecting within the area bounded by the container, and themselves delimiting an area of the size of 70 the rubber heel, but smaller than that of the leather base. These guide members or centering devices normally function to position the rubber heel correctly on a preceding leather base. When a leather base is secured 75 on top of the rubber heel and the plunger operated to force the two members downward, the guide members are engaged by the leather base, owing to its larger area, and opened or moved outwardly to permit 80 the passage by them of the leather base, after which they automatically move inward to engage over the upper edge surface of the leather base to prevent any upward movement of the heel blank resulting from 85 the natural spring of the material, especially the rubber after the pressure of the plunger has been removed.

As to the method involved, the invention resides in assembling a composite heel 90 blank of leather and rubber, in which the leather base is provided with a concaved upper side, whereby when the rubber heel is inserted on this concaved side of the leather base in the operation of making another heel blank, the lower edges of the rubber heel will engage the inclined wall of the concaved side of the leather base and thus be prevented from lateral movement.

The invention is illustrated in the accompanying drawing, in which—

Figure 1 is a vertical sectional view illustrating a portion of a machine of the type I prefer to employ in making the heel blanks, and showing a number of heel blanks within 105 the container of said machine;

Figure 2 is a plan view looking downward at the top of the container and showing a

leather lift or base in the position it occupies before being forced downward past the guide members;

Figure 3 is a broken sectional view taken 6 on the line 3—3 of Figure 2; and

Figure 4 is an enlarged detail broken sectional view to illustrate the manner in which the lower side of the rubber heel seats in the concaved portion of the preceding leather 10 base.

The machine shown in Figure 1 is of a well-known type, and will be found fully illustrated and described in the patent to Parks, No. 1,297,899, dated March 18th, 1919, 15 and also in my pending application, Serial No. 658,853, filed August 23rd, 1923. Only sufficient of this machine is shown to illustrate the operation. It comprises, essentially, a cross-head 1, which is continuously 20 reciprocated by a cam 2, working against a roller 3, mounted at the upper end of the cross-head, the roller being held in contact with the cam by means of a coil spring 4, and the cam being rotated by means of a 25 power shaft 5. Suspended on the cross-head by hooks 6 is an actuating plate 7, which is normally drawn inward toward a plunger frame 8 by means of coil springs 9, connected at their upper ends to the actuating plate 30 and at their lower ends to the cross-head. Pivotal mounted at 10 on the cross-head is a dog 11, having a hook 12 at its lower end, which is adapted to engage a lug 13 on the 35 upper part of the actuating plate 7, this movement being effected, in a certain position of the plate, by coil springs 14, connected at their lower ends to the cross-head and at their upper ends to projections 15 on said dog. The said dog is also provided 40 with a handle 16 for releasing it from engagement with the lug 13. The plunger frame 8 is provided on its front face with a shoulder 17, adapted to be engaged by the lower edge of the actuating plate 7, and has 45 mounted on its lower side a presser head 18. Mounted in line with this presser head, below it, is a container 19 consisting, essentially, of a front or breast plate 20 and two angle bars 21 (Figure 2), the breast plate and 50 angle bars confining an area of substantially the size of the heel blank to be inserted. The container, as a whole, is supported on a table 22, which is adjustable as to height by means of set screws 23. The plunger frame 8 has 55 connected to it pull rods 24, which extend downward to a treadle (not shown).

Assuming a heel lift to have been assembled on top of the container 19, the treadle is depressed to lower the presser head 18 60 into engagement with the top of the heel blank. When this occurs, the shoulder 17 on the plunger frame passes below the plane of the bottom of the actuating plate 7. The operator now grasps the handle 16 and pulls 65 it outward to move the hook 12 out of en-

gagement with the dog 13 when the springs 9 act to throw the lower end of plate 7 inward above the shoulder 17, and as the cross-head moves downward under the action of cam 2, the presser head will be moved downward to force the heel blank downward in the container. The parts automatically assume the position shown in Figure 1 when the cross-head moves upward.

In order to center the rubber heel with 75 respect to the leather base, I provide the construction now to be described, referring particularly to Figures 2 and 3.

Secured within the container at the corner of each of the angle bars 21 is a spring arm 25, having at its upper end a head 26, provided on its inner side with an inclined face 27, which terminates in the plane of a shoulder 28. The spring arms 25 with the heads 26 form two of the yielding guides or 80 centering devices for positioning the rubber heel. The other two centering devices are located toward the front of the container on either side thereof, and each comprises a bell-crank 29 pivotally mounted at 30 on an 85 adjustable bracket plate 31, one arm 32 of said bell-crank having a head 33, provided with an inclined inner face 34 projecting into the container, and the other arm 35 having a cup bearing 36 in its outer end, 90 which houses a coil spring 37, the lower end of which bears against the base of the plate 31. This spring normally holds the head 33 95 in its inward or guiding position, as shown by Figure 3.

Adjusting screws 38, passing through slots in the wall 20 of the container and engaging in the bracket plates 31, enable the bell-crank or centering devices 29 to be adjusted for different sizes of heel blanks.

The normal positions of the centering heads 28 and 33 is such that when a rubber heel is inserted in the space between them, it will be properly positioned thereby by simple engagement with the faces of the heads and can be forced past the heads without moving them.

In operation, a rubber heel 39, having been positioned between the centering devices, as shown in Figure 3, a leather lift or base 40, having paste applied to its under surface, is then placed in position over the rubber heel. This leather base will be positioned by the inner edges of the angle bars 21 and by the side walls of the container at the front, as shown by Figure 2, and it will rest upon the inclined faces 34 of heads 33. The presser head 18 being lowered in the manner heretofore described, the rubber heel will be moved past the heads 33 and the leather base 40 will engage the inclined sides of these heads and force them outward, and the adjustment of the movement of the presser head is such that it reaches the termination of its downward throw when the 115 120 125 130

leather lift 40 passes beyond the lower edge of the heads 26 and 33. The heads 33 are provided with shoulders 41, and when the composite heel blank has reached the position shown by Figure 3, the heads 26 and 33 will be forced inward so that the shoulders 28 and 41 will engage over the upper edge portion of the leather base and thereby prevent any upward movement of the heel blanks, due to the spring of the material. This insures that the leather base and rubber heel will be maintained in firm engagement with each other at all times during the passage of the heel blanks through the container so as to cause them to be firmly united.

As shown by Figures 1 and 3, the rubber heel is of slightly less width and length than the leather base, and, except at the breast of the heel blank, the leather base projects beyond the sides of the rubber heel. It is obvious, therefore, that the rubber heel is not in engagement with the wall of the container except, perhaps, at the breast thereof, and that, unless means be provided for preventing it, the rubber heels in the container might become displaced in their passage through the container before the paste has had time to set and secure them firmly to the respective leather bases.

By assembling the parts of the heel blank in the manner described above, I am enabled, by taking advantage of the smaller size of the rubber heel relative to the leather base and of the concavity afforded by the randed side of the leather base, to insure that the rubber heel will always be maintained in its centered position on the leather base in the passage of the heel blanks through the container, or until the paste is set. This feature of the invention will be more clearly apparent from the detail sectional view of Figure 4, which shows parts of two superimposed heel blanks. As shown in this figure, each of the leather bases has on its upper side a rand 42 extending, as usual, around the outer edge portion of the leather base, which rand, as is well known, provides a concaved seat 43 on the upper side of the leather base. By placing the rubber heel in the container first and then positioning the leather base on the rubber heel with its concaved side upward, I can place the succeeding heel within this concaved seat, the wall of which latter, engaging the lower edge of the rubber heel, offers sufficient resistance, owing to the incline of the wall, to lateral movement of the rubber heel to prevent displacement thereof relative to the leather base on which it seats.

I have found, in practice, that this method of procedure insures against any relative movement between the rubber heel and leather base of each heel blank, so that as the heel blanks emerge from the bottom of the container, the leather base and rubber heel of each heel blank will have the same

relative position given them by the guides at the top of the container.

I claim:

1. In a machine for use in assembling composite heel blanks of rubber and leather, in combination with a container for receiving and maintaining the heel blanks in column formation and a movable presser head for forcing the heel blanks downward in the container, a series of yielding guide members located at the top of the container and adapted when at rest to position the rubber heel inserted in the container and movable to permit the passage by them of a leather base applied to the rubber heel and larger than the same.

2. In a machine for use in assembling the parts of a composite heel blank of leather and rubber in which the leather member is larger than the rubber, in combination with a container for receiving and maintaining the heel blanks in column formation and a movable presser head for forcing the heel blanks downward in the container, means for positioning the leather base in the container, and yieldable centering devices normally projecting within the confines of the area occupied by the leather base and operating when at rest to center the rubber heel in the container.

3. In a machine for use in assembling the parts of a composite heel blank of leather and rubber in which the leather member is larger than the rubber, in combination with a container for receiving and maintaining the heel blanks in column formation and a movable presser head for forcing the heel blanks downward in the container, stationary means for positioning the leather base in the container, and yieldable centering devices normally projecting within the confines of the area occupied by the leather base and operating when at rest to center the rubber heel in the container.

4. In a machine for use in assembling the parts of a composite heel blank of leather and rubber in which the leather member is larger than the rubber, in combination with a container for receiving and maintaining the heel blanks in column formation and a movable presser head for forcing the heel blanks downward in the container, means for positioning the leather base in the container, and yieldable centering devices and operating when at rest to center the rubber heel in the container, each of said devices presenting on its inner side an inclined face normally projecting within the confines of the area occupied by the leather base.

5. In a machine for use in assembling the parts of a composite heel blank of leather and rubber in which the leather member is larger than the rubber, in combination with a container for receiving and maintaining the heel blanks in column formation and a

movable presser head for forcing the heel blanks downward in the container, means for positioning the leather base in the container, and yieldable centering devices and operating when at rest to center the rubber heel in the container, each of said devices having a head affording a shoulder for engaging over the leather base and an inclined face normally projecting within the confines of the area occupied by the leather base.

6. In a machine for use in assembling the parts of a composite heel blank of leather and rubber in which the leather member is larger than the rubber, in combination with a container for receiving and maintaining the heel blanks in column formation and a movable presser head for forcing the heel blanks downward in the container, means for positioning the leather base in the container, and spring-controlled centering devices and operating when at rest to center the rubber heel in the container, each of said centering devices presenting an inclined face normally projecting within the confines of the area occupied by the leather base.

7. In a machine for use in assembling the parts of a composite heel blank of leather and rubber in which the leather member is larger than the rubber, in combination with a container for receiving and maintaining the heel blanks in column formation and a

movable presser head for forcing the heel blanks downward in the container, means for positioning the leather base in the container, spring-controlled means located, respectively, at the breast and rear side of said container and operating when at rest to center the rubber heel in the container, each of said devices presenting an inclined face normally projecting within the confines of the area occupied by the leather base, and means for adjusting the position of the centering devices located at the breast side of the container to increase or decrease the space delimited thereby.

8. In the art of manufacturing composite heel blanks, consisting of a leather base and rubber heel, and in which the rubber heel is of less area than the leather base, the method which consists in positioning a rubber heel in a container, superimposing the flat side of a randed leather lift or base on the rubber heel with the interposition of paste, forcing the assembled members downward in the container, positioning a rubber heel on the concaved side of the leather lift or base and within the concavity formed by the rand thereof, then pasting a leather base to the last-named rubber heel, and continuing the foregoing operations.

In testimony whereof, I have hereunto set my hand.

DENNIS PARKS.
